UNITED STATES PATENT OFFICE.

LEOPOLD S. SAMUEL, OF NEWARK, NEW JERSEY.

PAD FOR FOOTWEAR.

1,036,911.

Specification of Letters Patent.

Patented Aug. 27, 1912.

Application filed July 29, 1911. Serial No. 641,353.

To all whom it may concern:

Be it known that I, LEOPOLD S. SAMUEL, a citizen of the United States, residing at Newark, in the county of Essex and State 5 of New Jersey, have invented certain new and useful Improvements in Pads for Footwear; and I do hereby declare the following to be a full, clear, and exact description of the invention, such as will enable others 10 skilled in the art to which it appertains to make and use the same, reference being had to the accompanying drawing, and to figures of reference marked thereon, which form a part of this specification.

15 This invention relates to a protective pad or plate to be used on the bottom of shoes, being particularly adapted to take up the wear and also to take up the shock so that when applied to a pair of shoes they cause 20 the wearer more comfort than with a pair of shoes not equipped with these devices.

The invention is further designed to provide an article of this kind which does not necessitate the use of nails or brads in the 25 fixing of it to the shoe, whereby the services of a shoemaker or repairer is not necessary to place the device on the shoe.

The invention is further designed to provide an article of this kind which is caused 30 to adhere to the shoe and can be made so that it will adhere closely at all points, thus minimizing wear and friction between its parts on account of the close application of the parts to each other and the close application of these parts to the shoe.

The invention is illustrated in the accompanying drawing, in which—

Figure 1 is a view of part of a heel in side elevation with one form of my pad secured thereto, and Fig. 2 is a top view of the pad flattened out. Fig. 3 is a side view of a pad to be used as the pads in Figs. 1 and 2, but of a modified form of construction. Fig. 4 is a view of the pad which is also straightened out and which is equipped with a particular kind of means for securing it to the heel of the shoe, and Fig. 5 is a view of a pad shown in Fig. 4 affixed to the heel of a shoe, the heel being shown in elevation 50 and the pad in section.

The article described herein is illustrated in simple forms showing the most practical shapes I have in mind, but I realize that the device can be made in ornamental form,

and can be shaped and designed so as to 55 give a good appearance to footwear to which it is applied.

The article is designed to be a pad that is resilient, the degree of resiliency not being specified, since I desire to use, in the pad, 60 different articles with different degrees of resiliency, depending on whether the wearer desires a pad for taking up the shock in walking, or one in which the wearer desires to take up the wear.

I prefer to fasten the pad to the bottom of footwear by suitable adhesive layers or adhesive strips which can be disposed in numerous ways to best secure the desired result. In making these pads I can either employ a single sheet of material which is provided with an adhesive layer or strip for fastening it to the bottom of the shoe, that is, to the sole or the heel, or I may use layers of different materials, as will be described 75 hereinafter.

In Fig. 1 is shown a pad having a wearing layer 21 which may be made of leather, rubber, felt or any other material suitable for the purpose and a resilient layer 22 which 80 is made of material having considerable elasticity. The adhesive 23 is in the form of a strip which passes, as at 24, between the layers 21 and 22 and serves to bind them together, and at its projecting ends 25 85 and 26 it is adapted to be pasted or caused to adhere to the shoe at points beyond the edges of the pad so as to secure the pad in position.

In Fig. 3 is shown a pad with an adhesive 90 strip 27 fastened to a wearing layer 28, said wearing layer being of any suitable material according to the purposes for which the pad is worn.

In Figs. 4 and 5 is still another modified 95 form in which the pad is made up of a resilient layer 29 and a wearing layer 30 which are held together by the adhesive strip 31 which extends beyond the edge of the pad as at 32 and is placed on the outside 100 of the heel and is provided in turn with a strip 33 adapted to go around on the sides of the heel, the strip 33 being an adhesive strip or a strip provided with adhesive so that it is tightly bound to the heel of the 105 shoe.

It will be evident that the elements that go on the outside of the heel, that is, on the

sides of the heel, or which might be carried up on the outside of the shoe, can be made ornamental in a great many ways and would add to, rather than detract from, the looks of the footwear to which it was applied.

5 The adhesive I use can be of any kind, and for footwear used in the house or in dry places, it can be of soluble material if desired, but for outdoor wear I prefer to 10 use adhesive that is water-proof.

10 I do not wish to be understood as limiting myself to simple pads for covering parts of the bottom of the footwear, since these pads may be made as layers to cover 15 the entire sole or heel of a shoe and might be made in excess of the surface to be covered, and then trimmed along the edge of the shoe to make a neat appearance at the edges.

20 Having thus described my invention, what I claim is:—

1. A pad for footwear consisting of a wearing layer, a resilient layer adapted to be placed between the wearing layer and the 25 footwear, means for securing these layers together, and an adhesive strip adapted to extend on the sides of the footwear and secured to the pad to secure the pad to the footwear.

30 2. A pad for footwear comprising a wearing layer, a strip secured to the pad and adapted to extend on the outside of the heel of a shoe, and a strip provided with an adhesive, said strip being adapted to embrace

the sides of the heel for securing the pad 35 to the footwear.

3. A pad for footwear consisting of a wearing layer, a resilient layer, and an adhesive strip between them to hold them together, said strip being adapted to extend 40 up on the exterior of the footwear to attach the pad to the bottom of the footwear.

4. A pad for footwear comprising a wearing layer, a resilient layer, an adhesive strip between the layers to secure them together, 45 said strip being adapted to pass upward on the outside of a heel, and a second strip, said second strip being provided with adhesive and being adapted to be passed around the sides of the heel to secure the pad to 50 the footwear.

5. A pad for footwear consisting of a layer of felted material, a wearing layer secured to the felted layer, and an adhesive strip secured to the pad and extending 55 therefrom for securing the pad to the footwear.

6. A pad for footwear comprising a resilient layer, and an adhesive layer secured to the pad and extending beyond the edges 60 of the pad for securing it to the footwear.

In testimony, that I claim the foregoing, I have hereunto set my hand this 28th day of July 1911.

LEOPOLD S. SAMUEL.
